(57) **CLAIM**

The ornamental design for a thigh train machine as shown and described.

DESCRIPTION

FIG. 1 is a top, front perspective view of a thigh train machine showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, rear perspective view thereof;

FIG. 9 is an enlarged detail view taken from portion 9 of FIG. 1; and,

FIG. 10 is an enlarged detail view taken from portion 10 of FIG. 1.

The broken lines encircling portions of the thigh train machine in FIG. 1 and illustrated in enlarged views in FIGS. 9 and 10 form no part of the claimed design.

1 Claim, 10 Drawing Sheets
